UNITED STATES PATENT OFFICE

162,266

MOTORBOAT

Walter Wiggins, Jr., Washington, D. C.

Application September 5, 1950, Serial No. 12,052

Term of patent 14 years

(Cl. D71—1)

To all whom it may concern:

Be it known that I, Walter Wiggins, Jr., a citizen of the United States, residing at Washington, in the District of Columbia, have invented a new, original, and ornamental Design for a Motorboat, of which the following is a specification, reference being had to the accompanying drawing, forming part thereof.

I claim:

The ornamental design for a motorboat, as shown.

WALTER WIGGINS, JR.
